HENRY MARK DELACOUR, OF ALBANY, NEW YORK, ASSIGNOR TO NEW YORK POWER & LIGHT CORPORATION, OF ALBANY, NEW YORK, A CORPORATION OF NEW YORK

GARBAGE INCINERATOR AND PROCESS

Application filed October 23, 1929. Serial No. 401,800.

This invention relates to a garbage incinerator and process. An object of the invention is to burn garbage in a closed incinerator in such a manner as to completely eliminate any offensive odors which may be produced in the burning process. In carrying out this process the garbage is placed within the container which is surrounded by another container or jacket spaced therefrom and in igniting the garbage and conducting the products of combustion including the offensive gases from the inner container downwardly and in contact with the highly heated portions of the same and thence upwardly to a flue which opens into the chimney or into the atmosphere.

A further object is to devise a simple and efficient incinerator for the rapid and efficient disposal of garbage by burning.

In the drawings, which are made a part of this application and in which similar reference characters indicate similar parts,

Fig. 1 is a front elevation of the incinerator with a portion of the outer shell or jacket broken away and a part of the cover shown in section,

Fig. 2 is an elevation of the incinerator at right angles to that shown in Fig. 1 and showing a portion of the outer shell or jacket broken away and also a portion of the inner shell broken away to clearly disclose the opening in the inner container permitting the gases to pass into the space between the inner container and the outer shell or jacket,

Fig. 3 is a plan view of the incinerator, and

Fig. 4 is a section on the line 4—4 of Fig. 2. The incinerator consists of an inner container 1 which is cone shaped at its lower portion and terminates in a cylindrical portion at the top. The container is mounted upon and supported by a base 2 and is suitably attached thereto by means of rivets or bolts 3 extending through the bottom flanged portion thereof as indicated at 4. The base 45 portion 2 consists of a cylindrical portion provided at its upper end with an in-turned annular flange upon which the container 1 is mounted. Within the opening in the flange of the base is located in any suitable manner 50 a movable grate 5 as shown clearly in Fig. 4.

The base 2 is also provided with a door 6 which admits of access to the ash pit within the base. The outer jacket 7 of cylindrical form surrounds the base 2 and extends upwardly to substantially the same level as the top of the container 1. This outer jacket or shell may terminate substantially at the top of the base 2 but for convenience it is extended downwardly to the bottom of the base. The annular space between the tops of the outer jacket and the inner container is closed by an annular plate or cover 8 which is provided with a collar or flue extension 9 through which the products of combustion pass outwardly to a chimney or directly into the atmosphere. The opening in the top of the inner container is closed by means of a pivoted cover 10. The garbage is introduced into the inner receptacle or container through its open top and when the cover 10 is placed in position the upper end is closed substantially air-tight. The inner container is provided with an opening 11 which permits the products of combustion to pass from the inner container into the space between it and the outer shell or jacket. This opening is located near the top of the apparatus. The inner container is also provided with a collar for extension 12 which extends outwardly through the wall of the outer jacket and provides an opening for the insertion of a burner or burners 13. These burners may be designed for use of oil in which case they are of the injector type or if gas is used as a fuel they are preferably of the Bunsen type.

Between the inner and the outer shells are located two baffles or division plates 14 which extend from the cover 8 downwardly and terminate a short distance above the top of the base 2 leaving openings for the passage of the products of combustion under the lower ends of the same. These baffles are located on opposite sides of the incinerator and divide the space between the two shells into two chambers. The opening 11 admits the products of combustion into one chamber from which they pass downwardly under the lower ends of the baffle plates and thence upwardly to the flue connection 9. The baffles 14 may be cast integral with the inner shell 1 as indicated at 100

cated in Fig. 4 and may be attached to the outer shell by means of suitable rivets or screws as indicated at 15. It will be noted that the opening 11 and the collar or extension 5 12 for the reception of the burners and the door 6 are located on one side which may be termed the front of the incinerator and the flue outlet 9 is located on the opposite side.

The incinerator may be made either wholly 10 of cast or wrought iron or other suitable metals but it has been found desirable to make the inner container, the base and the top and cover of cast iron and the outer shell or jacket of wrought iron. The baffle plates 15 of course may be made as separate elements and suitably attached to the inner container and the outer shell. The top cover 8 and the base may be held together by means of rods or bolts in any suitable manner.

20 In the operation of the incinerator the garbage is placed in the inner container and the cover 10 closed. The burners are then ignited and ignite the garbage in the inner container. It will be apparent that that portion 25 of the container 1 adjacent the burners and particularly the lower portion of the container will be heated to an extremely high temperature by reason of the burners and also by reason of the heat developed by the combustion 30 of the garbage. The products of combustion which are charged with objectionable and offensive odors if permitted to escape are conducted through the opening 11 downwardly over the highly heated portion 35 of the outside of the inner container, under the lower ends of the baffles 14 and thence upwardly to the flue 9. The gases in passing from the highly heated portion of the inner container on their way to the flue will be subjected 40 to such a temperature as to substantially eliminate the offensive odors produced thereby. It will thus be seen that a new process for the elimination of offensive odors arising from burning garbage has been devised 45 as indicated above. The gases which pass through the opening 11 are passed directly over the highly heated lower portion of the inner container which subjects them to such temperature as to practically eliminate 50 the offensive odors arising therefrom.

It will be apparent that the products of combustion of the burning garbage are not allowed to mix with air until they have been subjected to the re-heating process by being 55 forced to pass in close contact with the highly heated lower portion of the inner container. In fact the products of combustion do not receive any air until they reach the outlet 9 except of course what is introduced through 60 the connection 12 and passes upwardly through the burning garbage.

In the apparatus described the gases formed by the combustion of the garbage are brought into contact with the hot portion of the incinerator and so are re-heated to a point

which prevents the discharge of existing offensive odors. It is an essential that the products of combustion be prevented as described from coming into contact with fresh air such as might come through the grate 70 from the ash pit. For this reason the annular space between the container and the outer container 7, is closed substantially air-tight.

It will be obvious to those skilled in the art that various other modifications may be made in my device without departing from the spirit of my invention and therefore I do not limit myself to what is shown in the drawings and described in the specification but only as set forth in the appended claims.

Having thus fully described my invention, what I claim as new and desire to secure by Letters Patent is:—

1. In an incinerator, an inner shell provided with a grate, an outer shell, a cover engaging the upper edges of both said shells, diametrically opposed baffles extending from said cover downwardly between and in contact with said shells, a base closing the space between the lower ends of said shells, said baffles terminating short of said base, a burner casing extending through the outer shell and into the inner shell above said grate, said inner shell having an opening in its side wall near the top and directly above said burner casing, said outer shell having an outlet opening at its top diametrically opposite said burner casing whereby the products of combustion will be conducted from the inner shell near its top downwards over the heated portion of said inner shell, under the lower ends of said baffles thence upwardly to said outlet.

2. In a garbage incinerator, two coaxial shells closed at the top, the annular space between said shells also being closed at the bottom, a grate in the bottom of the inner shell, said inner shell having an opening near its top into the space between said shells and another opening near its bottom for the reception of burner means, a burner casing extending from the outer shell to the inner shell and fitting in the burner opening in the inner shell, said outer shell having a flue opening at its top diametrically opposite the openings in said inner shell, a pair of vertical baffles extending from the top of said shells downwardly and terminating short of the bottom of said annular space, whereby products of combustion are led from said inner shell downwardly under said baffles and thence upwardly to said flue opening.

3. In an incinerator, a base having a closed ash pit therein, an inner and an outer shell mounted thereon, said shells closed at the top and providing a closed chamber therebetween, opposed baffles between said shells and dividing said chamber into front and rear sections, said inner shell provided with an upper opening into said front chamber

section and a lower opening, a casing in said lower opening and leading through said front chamber section and through said outer shell for the reception of burner means, said rear chamber section provided with a flue opening 5 in its upper portion, said baffles arranged at their lower ends to provide openings from said front to said rear chamber sections.

4. In a garbage incinerator, in combination, a base providing a closed ash pit and having a grate in the central portion thereof, a garbage container attached to said base and surrounding said grate, an outer shell surrounding said base and extending upwardly concentric with said container, a cover member in contact with the upper ends of 10 said shell and said container, said container provided with two openings vertically aligned the upper opening permitting products of combustion to enter the chamber formed between said container and said shell, the lower opening provided with a collar extending through said shell for the reception of burner means, said cover member provided with 15 a flue opening on the side of said incinerator opposite said aligned openings, a pair of baffles extending from said cover member downwardly in contact with said container and said shell and stopping short of said 20 base.

5. In a garbage incinerator, in combination, a base provided with a grate and a closed ash pit, a garbage container mounted on said base and enclosing said grate, said 25 container being cone shaped at its lower portion terminating in an upper open ended cylindrical portion, an outer shell in contact with said base, a cover connecting the upper ends of said outer shell and said container, said container having an opening provided 30 with a collar extending through said outer shell, to receive burner means, and with an opening near its top vertically above said first opening, a flue connection in said cover opposite said openings and vertical baffles 35 extending from said cover downwardly between said shell and said container and in contact with both and terminating above said base.

6. In a garbage incinerator, a base provided with a central grate, a garbage container mounted on said base above said grate, said container having integral diametrically opposed baffles extending from its upper end 55 and terminating short of its lower end, an outer shell mounted on said base and surrounding said container, the annular space between the upper ends of said container and shell being provided with a cover having a flue opening, a movable cover for the upper 60 end of said container, said container having a side opening near its top opposite said flue opening and being provided near its bottom with a connection extending through said 65 shell for the reception of burner means.

7. In a garbage incinerator, a base provided with a grate and ash pit and closed from the atmosphere, an open ended garbage container mounted on said base over said grate, an outer shell mounted on said base 70 and surrounding said container, a cover for the space between the upper ends of said shell and said container, a cover for the upper end of said container, said first mentioned cover provided with a flue opening, 75 said container having an opening near its top and opposite said flue opening, a pair of vertical baffles between said shell and container, extending from the top thereof to within a short distance of said base and means 80 for the reception of a burner for igniting the garbage in said container.

In testimony whereof I affix my signature.
HENRY MARK DELACOUR.
